UNITED STATES PATENT OFFICE.

JOHN R. GAMMETER, OF AKRON, OHIO, ASSIGNOR TO THE B. F. GOODRICH COMPANY, OF NEW YORK, N. Y., A CORPORATION OF NEW YORK.

METHOD AND MACHINE FOR SEWING RUBBER.

1,284,646.

Specification of Letters Patent.

Patented Nov. 12, 1918.

Application filed February 8, 1918. Serial No. 215,961.

To all whom it may concern:

Be it known that I, JOHN R. GAMMETER, a citizen of the United States, residing at Akron, in the county of Summit and State of Ohio, have invented a certain new and useful Method and Machine for Sewing Rubber, of which the following is a specification.

This invention relates to the art of sewing material containing rubber or allied gums, and its subject-matter is an improved mode of forming stitch-holes in the work. Considerable difficulty has heretofore been experienced in sewing vulcanized rubber, and particularly shoe soles composed of rubber mixed with ground-up vegetable fiber, because the awl or needle of the sewing machine tends to tear the edges of the hole which it drives in the sole, and the thread 10 does not run with ease through the hole on account of its friction against the rubber. When the ends of the loops have been worn off from the bottom of the seam, the stubs of the thread often tend to pull out of their 15 holes, allowing the sole to separate from the body of the shoe. In order to minimize these difficulties as far as possible it has been necessary to employ a higher grade of rubber and more and better fiber than would 20 be required to give sufficient durability to the sole. The high-grade rubber is costly, and the large content of fiber introduces obstacles in the working of the material.

My invention has for its object to overcome the difficulties mentioned, and it does so by making use of a heated penetrating instrument whose passage into or through the rubber-containing material softens or partially fuses the latter, producing a 25 smooth hole of the desired round or other shape, lubricating the thread during the sewing operation and locking it securely in the seam by the subsequent hardening or setting of the rubber around the thread.

40 Of the accompanying drawings, Figure 1 is an elevation, partly in section, showing the main working parts of a sewing-machine provided with an electrically heated awl or penetrating instrument for embodying and carrying out my invention, together with a section of the work being operated on.

Fig. 2 is a side elevation.

Figs. 3 and 4 are sections on the correspondingly-numbered lines of Fig. 1.

10 represents a portion of a shoe-sole of vulcanized rubber and fiber composite, and 11 represents the welt or corresponding part of the shoe to which the sole is being sewed. 12 is the usual sewing-machine awl 60 which acts in the capacity of a perforating instrument and also as a work-feeder, being attached to an awl-bar 13 to which vertical reciprocation is imparted by an oscillating arm 14 and horizontal reciprocation by another arm 15. Member 12 may be termed the "cold-awl." 16 is the presser foot. 17 is the revolving shuttle carrying the spool or bobbin 18 for the thread 19, and 20 is the vertically-reciprocating sewing-needle. 21 70 is the work-supporting table or bed having a slot 22 for the passage of the awl and needle. These parts are all of familiar construction and operation.

The lower part of the awl-bar 13 forms 75 a suitable support for the electrical heater 23 and the hot-awl or needle 24 embodying my invention, which element 24 it will be noted is shorter than the main awl 12 and penetrates only the rubber sole 10, being 80 shown substantially in its lowest position in Fig. 1. While the main awl (or even the sewing needle) could be heated instead of providing a separate member 24, the arrangement shown prevents the leather of the welt 11 from being charred, relieves the hot-awl from any bending strain and allows the invention to be readily adapted to existing machines.

The axis of the heater 23 is preferably inclined at an angle from the vertical as shown, and the stem or extension 25 of the hot needle within said heater is correspondingly inclined to its active portion 24. This stem is suitably insulated, as by means of a mica sleeve or wrapping 26 carried in the bore of a porcelain holder 27, the latter being secured to the awl-bar 13 by two metal straps or bands 28. Stem 25 constitutes a resistance element attached at its upper end to an electrical connector 29 and at its lower end to a second electrical connector 30. Where the latter passes under the bands 28 it is protected by insulators 31.

The upper ends of the connectors 29, 30 105 are provided with tubular brush-holders or sockets 32, in which are mounted a pair of contact-brushes 33 backed by springs 34. These brushes slide against a pair of contact-strips 35 mounted on opposite sides of 110

a vertical insulating bar 36 which is stationarily mounted on the frame 37 of the machine, the strips 35 being of sufficient width to allow for the horizontal reciprocation of the needle-bar without losing contact with the brushes, and also being of sufficient height to allow for the vertical reciprocation of said bar and to reach a convenient upper locality for connection with the external circuit. 38, 38 represent the wires of the external circuit, leading from any suitable source of current, and 39 is a detachable plug comprising a suitable insulating body and a pair of contacts 40 engaging the strips 35.

In operation, the descent of the awl-bar 13 causes the awl 12 to penetrate both the sole 10 and the welt 11, and at the same time the electrically-heated awl or needle 24 penetrates the sole to or nearly to the welt as indicated in Fig. 1 its high temperature causing the rubber at the point of penetration to soften or melt and allow an easy entrance producing a smooth hole of the shape of said needle. The horizontal feeding motion of the awl-bar takes place while both members 12 and 24 are in the sole and the presser-foot 16 is retracted, Fig. 1 showing the parts at the completion of the feeding movement. 30 The presser-foot then descends, the awl-bar rises to withdraw both members 12 and 24 from the sole, the sewing needle 20 rises and passes through the hole left by the awl 12, engages the thread, descends and pulls down 35 a loop; the shuttle 17 passes through said loop and the thread is drawn tight from above in the usual way, thus completing a stitch. The hot needle 24 is spaced from the awl 12 a distance equal to the length of one 40 stitch, and when the awl 12 next descends it enters the hole which has been burned or fused in the sole 10 by said needle, and has only to force its way through the welt 11. Thus any tearing of the sole is avoided and 45 when the stitch is being formed the thread is more or less lubricated by the soft rubber on the sides of the hole. This rubber subsequently sets or hardens around the thread and cements it in place, so that the stubs of 50 the stitches do not readily pull out when their exposed portions are worn off on the bottom.

While I have represented a machine of the straight-needle type, it will be understood 55 that the invention may be used with any suitable form of sole-sewing machine, and the method may be performed by hand without any machine. Furthermore the invention is not wholly confined to the employment 60 of an electric current as the heating medium nor restricted to the several details of embodiment here shown by way of illustration.

I claim:

65 1. In a sewing machine, the combination

of stitch-forming mechanism, an awl for fusing holes for the stitches in the material to be sewed, and means for heating said awl.

2. In a sewing machine, the combination of stitch-forming mechanism, an awl for fusing holes for the stitches in the material to be sewed, and means for electrically heating said awl.

3. In a sewing machine, the combination of stitch-forming mechanism, a reciprocating awl and electrical heating resistance therefor, a stationary conductor for carrying current to said resistance and means for preserving an electrical connection between said conductor and the resistance during reciprocation of the latter.

4. In a sewing machine, the combination of stitch-forming mechanism, a reciprocating support, a metallic member mounted thereon and having an exposed extremity 85 adapted to penetrate and fuse the material to be sewed and an electrical resistance portion, insulating material inclosing said resistance portion, and means for conducting current to said resistance portion.

5. In a sewing machine, the combination of sewing mechanism, means for fusing holes part way through the work for the passage of the stitches, and means for cold-punching the continuations of said holes.

6. In a sewing-machine, the combination of sewing mechanism, a reciprocating support, a cold-awl carried thereby, a hot-awl also carried by said support, and means for heating said hot-awl.

7. In a sewing-machine, the combination of sewing mechanism, a reciprocating support, a cold-awl carried by said support, a hot-awl also carried thereby and terminating short of the termination of the cold-awl so as to penetrate the work for a less distance than the latter, and means for heating said hot-awl.

8. In a sewing-machine, the combination of a work support formed with a slot, a reciprocating cold-awl adapted to operate through said slot, a reciprocating hot-awl adapted to operate above said slot, and means for heating said hot-awl.

9. In a sewing-machine, the combination of sewing mechanism, a work support, a reciprocating hot-awl operating over said support for fusing stitch-holes part-way through the work, means for heating said awl, and a reciprocating cold-awl operating 115 over and through said support, said cold-awl being located in advance of the hot-awl in the direction of feed of the work and adapted to complete the holes started by the hot-awl.

10. In a sewing-machine, the combination of sewing mechanism, an awl support having a longitudinal reciprocating motion and also a lateral motion to feed the work, two awls carried by said support, the first being 120

125

130

shorter than the second and adapted to fuse part way through the work, holes which are completed by the second awl, and means for heating the first awl.

5. 11. In a sewing-machine, the combination of sewing mechanism, an awl support having a longitudinal reciprocating motion, a cold-awl carried by said support, a hot-awl mounted on said support adjacent to the cold-awl, a stem for said hot-awl, located at an angle thereto and constituting an electrical resistance, an insulating inclosure for said stem, and means for conducting current to said stem.

10. 12. In a sewing-machine, the combination of sewing mechanism, an awl support having a longitudinal reciprocating motion, a cold-

awl and a hot-awl carried by said support, an electric heater also carried thereby for heating the hot-awl, and means for conducting current to said hot-awl.

13. In a sewing-machine, the combination of sewing mechanism, an awl-support having longitudinal work-penetrating and lateral work-feeding motions, an awl and an electrical awl-heater carried by said support, a contact brush also carried thereby, and a stationary conductor on which said brush slides, said conductor having such length and breadth as to maintain constant connection with the contact-brush.

In testimony whereof I have hereunto set my hand this 4 day of February, 1918.

JOHN R. GAMMETER.
